UNITED STATES PATENT OFFICE.

WILLIAM RENARD PILKINGTON, OF BAMBER BRIDGE, NEAR PRESTON, ENGLAND,
AIR OR OTHER FLUID-PRESSURE PUMP.

1,160,528.

Specification of Letters Patent. Patented Nov. 16, 1915.

Application filed January 25, 1915. Serial No. 4,353.

To all whom it may concern:

Be it known that I, WILLIAM RENARD PILKINGTON, a subject of the King of Great Britain, residing at Dowry House, Bamber Bridge, near Preston, in the county of Lancaster, England, have invented certain new and useful Improvements in Air or other Fluid-Pressure Pumps, of which the following is a specification.

10 This invention relates to a foot operated air or other fluid pressure pump that is primarily intended for inflating the tires of motor or other vehicles, and the invention consists in the combination of a treadle pivoted at one side of a frame or base, an oscillatory cylinder pivoted at the other end of the frame or base with its piston rod making a toggle joint with the treadle, and a spring for normally retaining the treadle and cylinder in their raised or normal position.

In the accompanying drawings:—Figure 1 is a side elevation of a pump constructed in accordance with this invention. Fig. 2 is a side elevation showing the pump in its closed position. Fig. 3 is a plan, Fig. 4 an inverted plan and Fig. 5 an end view, of the pump. Fig. 6 is a side elevation and Fig. 7 a plan of a modified form of pump.

A indicates the pump cylinder, B, B, indicate two levers which constitute the treadle and are operatively connected with the pump piston and C indicates the frame of the pump.

In the example shown the cylinder A is pivoted at a to the base or frame which may be constructed of aluminium, aluminium alloy or other material. Pivoted at b to the base or frame C are two arms or levers B, B, these levers are connected at their outer end with a cross piece b^1 which may be fitted with india rubber studs b^2 or be otherwise constructed to prevent the foot from slipping therefrom when the apparatus is in use. The arms or levers B, B, extend over the top of the cylinder A and their free ends are conveniently cranked at b^3 to suit the position usually assumed by the foot during the pumping operation. The piston rod a^1 is connected at its outer end with a cross head a^2 which is pivoted between the arms or levers B, B, to allow the angular movement of such arms and the piston rod, and in order to retain such parts in their raised or normal position a spring b^4 is connected at one end to a rod b^5 extending between two cranked portions b^6 of the arms or levers

B, B. The outer end of the spring is connected to a cross bar c in the frame C by a bolt b^7 which passes through a hole in such cross bar and is secured by a nut b^8 . By this arrangement the pull exerted by the spring b^4 upon the arms or levers B, B, can be regulated as required. When the levers are in their raised position as shown in Fig. 1 the piston or plunger is at the outer end of its stroke and as the arms are forced downward against the action of the spring b^4 the piston is forced to the inner end of its stroke with a gradually increasing power due to the flattening of the angle assumed by the cylinder A and the operating arms B, B. When the pressure upon the latter is released, the spring b^4 returns the parts to the normal or original position. The frame or base may be formed with stops c^1 to limit the downward movement of the levers B, B, and may have cavities formed in its underside to receive india rubber or other pads for preventing the pump from shifting on the ground, floor or other surface when in use, or if desired its under surface may be roughened and be provided with points or other devices for effecting such purpose. The pump cylinder is as usual provided with a non-return valve and carries a pressure gage D communicating with the cylinder and with the connecting pipe d.

If desired a whistle or other indicator may be fitted for directing the attention of the operator when the tire is pumped to the required pressure.

When the pump is not in use it may be retained in its closed position as shown in Fig. 2. This is conveniently effected by a link b^9 pivoted at c^2 to the frame C and having an inclined slot b^{10} to engage an annular groove a^5 in a pin a^4 projecting from the cross head a^2 , the inclination of the slot b^{10} and the position of the pivot c^2 being such that when the pressure is exerted in a downward direction upon the cross piece b^1 the pin a^4 pushes the link b^9 to one side whereupon it falls against a stop a^3 on the frame C and upon releasing the pressure on the cross piece b^1 the parts assume the position shown in Fig. 1. The greater part of the friction that is set up by the turning movement of the various parts can to a great extent be eliminated by employing ball, roller or knife edge bearings.

In the modification shown in Figs. 6 and 7 the lever B is arranged in rigid connection

with an arm B^1 , pivoted at its free end to a trunk piston a^6 and such arm is curved as shown in Fig. 6 so that it will not bind against the piston as the latter is moved throughout its complete stroke. Rigidly connected with the arms B , B^1 is an arm b^6 similar to that shown in Figs. 1 and 2 and such arm is connected to one end of a spring b^4 of which the other end is connected by a bolt b^7 and nut b^8 to an arm a^6 forming part of or rigidly connected with the cylinder A . In this example the pivot a for the cylinder A is situated about the middle of the frame C and the lever B is of such a length that it will clear the end C^1 of the frame when the lever B is moved through a full stroke. The modification above described may be fitted with a link such as b^9 (see Figs. 1 and 2) for retaining the pump in its closed position. By constructing a pump in this manner great leverage is obtained and the pump occupies a very small amount of space when in its closed position.

The details of construction can be variously modified without departing from the nature of the invention, for example, in some cases it may be convenient to construct the pump cylinder with the operating arms and

if desired the cylinder and arms may be retained in their normal position by a pneumatic spring which might be combined with the piston rod or be arranged separately therefrom.

What I claim by my invention and desire to secure by Letters Patent in the United States is:—

In an air pump, a supporting frame, a pump cylinder pivoted to the frame and provided with a piston, an operating lever formed of a pair of arms pivoted to the frame and operatively connected with the pump piston and arranged to straddle the cylinder, said lever arms having lugs at their pivoted ends which project at an angle to their main portions, a rod extending crosswise between the said lugs, and a spring connected to the middle part of the said rod and to the said frame and operating to normally support the lever and cylinder with the piston at the outer end of its stroke.

In testimony whereof I affix my signature in presence of two witnesses.

WILLIAM RENARD PILKINGTON.
